UNITED STATES PATENT OFFICE.

SAMUEL N. POND, OF CHICAGO, ILLINOIS.

ROTARY PUMP.

1,243,215.

Specification of Letters Patent. Patented Oct. 16, 1917.

Application filed June 23, 1917. Serial No. 176,470.

To all whom it may concern:

Be it known that I, SAMUEL N. POND, a citizen of the United States, residing at Chicago, in the county of Cook and State 5 of Illinois, have invented certain new and useful Improvements in Rotary Pumps, of which the following, taken in connection with the accompanying drawing, is a specification.

10 This invention relates to rotary pumps for raising liquids or forcing the same through pipes or mains, and the chief purpose or object of the invention is to provide a pump capable of producing higher pressures, in proportion to its size and speed of operation, than can be obtained from the best types of rotary pumps now in use. Another object of the invention is to provide a rotary pump possessing increased efficiency 15 and economy of operation as compared with known liquid forcing devices of the same general character.

One known type of rotary pump operates on the principle of the displacement of the 20 liquid by centrifugal action through the agency of a rapidly revolving paddle wheel within a casing having a central intake and a peripheral discharge. Another known type operates on the principle of a screw, 25 wherein the liquid is bodily moved in a given direction through the agency of a rapidly revolving spiral or screw propeller confined and rotating within a cylindrical or conical casing having open ends for the 30 intake and discharge of the liquid.

35 The pump forming the subject matter of my present invention, as will readily be seen from the following description and the accompanying drawing, combines these two 40 principles harmoniously in a single structure, and yields results superior to any that are attainable with the best forms of either of these known types.

In order that my invention and its principle 45 of operation may be readily understood by those skilled in the art, I have, in the accompanying drawing, illustrated one practical form in which the invention may be embodied; and referring thereto—

50 Figure 1 is a side elevation, in section through the shaft and casing, of my improved pump.

Fig. 2 is a section taken on the line 2—2 of Fig. 1, and looking in the direction indicated by the arrows.

Referring to the drawing, 5 and 6 des-

ignate the mating halves of a casing of snail-shell form that are peripherally united by bolts or screws 7, the casing being formed with a suitable pedestal or base-block 8. The 60 casing is formed with an axial suction or intake opening 9 in the member 5 with which communicates a supply pipe 10, and preferably with a pair of oppositely disposed and directed tangential discharge openings or 65 passages 11.

Extending through a suitably packed joint 12 in the casing member 6 is a shaft 13 journaled in suitable bearings 14 and carrying fast and loose pulleys 15 and 16. Fast 70 on this shaft 13 within the casing is the rotor of skeleton form, and, as herein shown, embodying the following structural features. 17 designates each of a pair of rings that are rigidly connected and spaced at intervals 75 by cross-bars 18 and 19. The ring structure thus formed is connected to the hub portion 13' of the shaft 13 by a series of spokes 20 extending between said hub and the bars 18 and strongly and rigidly connected to both, 80 so that the rotative effort of the shaft is transmitted to the ring structure wholly through said spokes. The rotor further includes a series of radial vanes, each of which, as herein shown, comprises a spindle 85 21 journaled at its inner end in a suitable bearing in the hub 13' and at its outer end in a suitable bearing in one of the cross-bars 19, and one or more spiral blades 22 rigid with and encircling said spindle. 90

Rotation of the vanes on their individual axes simultaneously with the rotation of the rotor as a whole about the axis of shaft 13 is effected through the agency of pinions 23 fast on the outer end portions of the spindles 95 21 meshing with a stationary ring gear 24 integral with or secured to the inner side of one of the side walls of the casing. The pitch of the spiral blades is, of course, such as to effect an outward propelling or propulsive action in a radial direction under the described rotation of the blades on their individual axes.

The mode and principle of operation will be readily apparent from the description 105 and illustration. As the rotor is driven through power applied to the shaft 13, the individual vanes are not only carried bodily around the axis of the shaft, but they are also at the same time given a rapid rotation 110 on their individual axes; and since the edges of the spiral blades just clear the inner sur-

faces of the side walls of the casing, said 5 vanes operate to force the liquid outwardly both by centrifugal action and by a screw action, both actions taking place simultaneously upon the whirling body of liquid within the casing. This combined action effects a rapid and powerful displacement of the liquid radially of the rotor, creating a 10 strong continuous uniform flow through the discharge passage or passages 11, and a corresponding vacuum or suction effect at the intake opening 9.

My invention is useful not only as an efficient lifting or forcing device for liquids 15 such as water and oil, but it also constitutes a very effective mixing device for paints and the like in the manufacture of which two or more liquids require to be thoroughly mixed or comingled.

20 So far as I am aware, I am the first to combine in a rotary pump the centrifugal and screw principles of liquid propulsion operating simultaneously and coöperatively in a single structure. Such being the case, 25 I do not limit myself herein to the particular form and structure of apparatus illustrated and described, but reserve all such variations and modifications as may fairly fall within the spirit and purview of the invention as defined in the appended claims.

I claim:

1. In a rotary pump, the combination with a pump casing having an axial intake

and a peripheral discharge, of a rotor journaled to rotate in said casing and provided 35 with radial vanes, each of spiral or screw form and capable of rotation on its own axis, and means for imparting individual rotation to said vanes simultaneously with the rotation of said rotor about its own axis. 40

2. In a rotary pump, the combination with a pump casing having an axial intake and a peripheral discharge, of a rotor journaled to rotate in said casing and provided with radial vanes, each of spiral or screw 45 form and capable of rotation on its own axis, a stationary ring gear at one side of said rotor, and gears fast on said vanes engaging said ring gear to impart individual rotation to said vanes simultaneously with the rotation of said rotor about its own axis. 50

3. In a rotary pump, the combination with a pump casing of snail-shell form having an axial intake and a tangential peripheral discharge, of a rotor journaled to rotate 55 in said casing, radial spindles journaled at their ends in the hub and rim of said rotor, spiral blades rigid with and encircling said spindles, a stationary ring gear on the inner side of one side wall of said casing, and 60 gears fast on said spindles engaging said ring gear to impart individual rotation to said spindles and their spiral blades simultaneously with the rotation of said rotor about its own axis.

SAMUEL N. POND.
